(57) **CLAIM**

The ornamental design for a palm based photosensor instrumentation, as shown.

DESCRIPTION

FIG. 1 is a perspective view of a unit according to the invention;

FIG. 2 is a top view of the design of the invention;

FIG. 3 is a first side elevation view of the design of the invention;

FIG. 4 is a back elevation view of the design of the invention;

FIG. 5 is front elevation view of the design according to the invention;

FIG. 6 is a second side elevation view of the design according to the invention; and,

FIG. 7 is a bottom view of the design according to the invention.

1 Claim, 6 Drawing Sheets

FIG. 1

FIG. 2***FIG. 3***

FIG. 4

FIG. 5

FIG. 6

FIG. 7
